UNITED STATES PATENT OFFICE.

EMANUEL W. SWEIGARD, OF CHICAGO, ILLINOIS.

PRINTING-FRAME.

No. 824,757.

Specification of Letters Patent.

Patented July 3, 1906.

Application filed October 7, 1905. Serial No. 281,720.

To all whom it may concern:

Be it known that I, EMANUEL W. SWEIGARD, a citizen of the United States of America, residing at Chicago, in the county of 5 Cook and State of Illinois, have invented certain new and useful Improvements in Printing-Frames, of which the following is a specification.

My invention relates to improvements in 10 printing-frames, and is fully described and explained in this specification and shown in the accompanying drawings, in which—

Figure 1 is a transverse section through my improved printing-frame. Fig. 2 is a top 15 plan of the backboard thereof. Fig. 3 is a section in the line 3 3 of Fig. 2. Fig. 4 is a section in the line 4 4 of Fig. 2, and Fig. 5 is a section in the line 5 5 of Fig. 4.

Referring to the drawings, A is a hollow 20 rectangular frame of the ordinary sort, such as is used in photo-engraving, the same being provided with a thick glass plate B at its front and at its back with a plurality of hinged pressure-bars C, having mechanism 25 for clamping them down. In making photo-engravings and the like a photograph-negative of the ordinary sort is first made and after that a print on a metal plate, usually of zinc. In making this plate it is necessary 30 that the metal plate and the negative be brought into as close contact as is accomplished in ordinary printing between the paper and the negative. To effect such a close contact requires a degree of pressure re- 35 quiring special appliances and backboards of exceptional strength. My invention resides in the backboard of the device, which I will now describe.

A plurality of sections D D', trapezoidal in 40 cross-section, are first glued together to form a board. By building up the board in this way unusual strength and firmness are obtained and little tendency to warp. Along the ends of the board thus formed (and in the 45 middle also, if the board is large) are secured cleats E, the said cleats being secured to the board by means of screws E', passed through perforations in the board and through rubber sleeves e in said perforations. The lower 50 faces of the board are countersunk at e', so that the heads of the screws E' will lie below the face of the board, so as not to interrupt its smooth surface, and said countersunk spaces e' contain two perforated plates, an 55 upper plate e² and a lower plate e³. The perforation in the lower plate fits the screw;

but the perforation in the upper plate is somewhat larger, so as to admit of considerable lateral movement of the screw therein. In use these backboards receive all sorts of 60 bad treatment, being frequently soaked and subjected to every kind of warping influence. The cleats being on the upper faces of the boards and being more exposed to the air are usually drier than the main portions of the 65 boards, and as a result the cleats cause rather than prevent warping. With my construction, however, when the boards are wet and swell and the cleats do not elongate the 70 boards can slide on the cleats, the connecting-screws E' moving laterally in the perforations provided for the purpose and compressing the small rubber sleeves which surround them. Simultaneously the two metal plates e² e³ can slide on each other, so that the 75 boards are permitted to elongate independently of the cleats. The cleats are, however, firmly clamped to the boards, so as to prevent warping thereof.

It is necessary to interpose some kind of an 80 elastic spring between the presser-bars and the backboards of these frames, and it has been exceedingly difficult to find a suitable elastic substance. If a solid block of 85 comparatively hard rubber be used, it is not sufficiently elastic, while if softer rubber be used it is not sufficiently durable. As an elastic medium in my device I provide a plurality of rubber cylinders F, each of which is provided with a number of vertical perforations f and 90 a single central perforation f', which fits tightly over the head of a screw f², holding the cylinder in place. Depressions are formed below the cylinders in the face of the board, which depressions are adapted to receive the lower ends of the cylinders when 95 pressure is applied thereto. I find that these cylinders are extremely elastic and exceedingly durable.

I claim as new and desire to secure by Letters Patent—

1. In printing-frames, a backboard comprising a plurality of sections trapezoidal in cross-section, secured together with their parallel faces on opposite sides of the board 105 and their broad and narrow parallel faces alternating.

2. In printing-frames, a backboard, cleats on the backboard and means for securing the cleats to the backboard so as to have a limited 110 longitudinal movement with respect to the backboard.

3. In printing-frames, a backboard, cleats on the backboard, and screws passed through the backboard and securing the cleats thereto, the perforations for said screws being of larger diameter than the screws themselves.

4. In printing-frames, a backboard, cleats on the backboard, screws passed through the backboard and securing the cleats thereto, the perforations for said screws being of larger diameter than the screws themselves, and elastic sleeves surrounding the screws.

5. In printing-frames, a backboard, cleats on the backboard, screws passed through the backboard and securing the cleats thereto, the perforations for said screws being of larger diameter than the screws themselves, and rubber sleeves surrounding the screws.

6. In printing-frames, a backboard countersunk on its lower surface and perforated

coaxially with the countersunk spaces, rubber sleeves in the perforations, two washers in the countersunk spaces, one of which is movable, and screws passed through the washers, and a cleat which the screws enter.

7. In printing-frames, a backboard, having depressions on its faces, a clamp, and transversely - perforated rubber blocks of larger diameter than the depressions arranged between the backboard and clamp and above the depressions.

In witness whereof I have signed the above application for Letters Patent, at Chicago, in the county of Cook and State of Illinois, this 4th day of October, A. D. 1905.

EMANUEL W. SWEIGARD.
